UNITED STATES PATENT OFFICE

IRA W. NONNEMAN, OF WARREN, OHIO, ASSIGNOR TO THE BORDEN COMPANY, OF WARREN, OHIO, A CORPORATION OF OHIO.

DIESTOCK.

1,404,997.

Specification of Letters Patent. Patented Jan. 31, 1922.

Application filed February 9, 1920. Serial No. 357,235.

To all whom it may concern:

Be it known that I, IRA W. NONNEMAN, a citizen of the United States, residing at Warren, in the county of Trumbull and 5 State of Ohio, have invented a certain new and useful Improvement in Diestocks, of which the following is a full, clear, and exact description, reference being had to the accompanying drawings.

10 This invention relates to die stocks in which the recession of the chasers is governed by the movement of the chaser carrying frame along the pipe being threaded, and is more particularly concerned with 15 that type of die stocks in which a guiding frame is clamped to the pipe and has a threaded engagement with the chaser carrying frame to insure accurate advancement of the chasers along the pipe, there being 20 connections between the guide frame and the chaser carrying frame for causing the progressive recession of the chasers.

The objects of the present invention include the provision of a simple cheap construction. A more specific object is to provide for adjusting the chasers inwardly and outwardly with relation to the pipe to be threaded to accomplish accurate sizing of the threads to exact standard size while 30 permitting cutting over and under-sized threads as desired. A preferred embodiment of my invention is illustrated in the drawings in connection with which my invention is hereinafter more fully explained, 35 the essential characteristics thereof are summarized in the claims.

Fig. 1 is a face or front view of the die stock; Fig. 2 is a side elevation of the same; Fig. 3 illustrates the cam plate for adjusting 40 the grippers of the guiding frame; Fig. 4 is a view similar to Fig. 1 with the front plates removed showing the construction of the chasers and the adjusting means therefor; Fig. 5 is a detail of one of the chasers; 45 Figs. 6 and 7 are details of yokes each adapted to engage two chasers and connected with adjusting screws; Fig. 8 is an enlarged sectional detail through the frame illustrating the chaser receding control 50 mechanism.

The chaser carrying frame is shown as a casting having concentric annular flanges 1 and 2 rising from a web plate 3 with which they are integrally formed; while 55 projecting outwardly from opposite sides

of the frame are sockets 5 preferably internally threaded to receive the die stock handles 6.

The flanges 1 and 2 are provided with radial slots adapted to receive chasers 10 60 each of which has a flat face 11 adapted to rest against the plate 3 and having offset surfaces 12 and 13 to provide for receiving a yoke or bridge member 15. These yokes are shown as extending partially around the 65 flange 3, and as each having legs extending over two of the chasers, abutting a shoulder 14 between the surfaces 12 and 13, and each yoke has its opposite ends resting against and in sliding engagement with guide 70 flanges 7 forming integral parts of the chaser carrying frame. Intermediate of the legs of the yoke is provided a boss 20 internally threaded to receive screws 21 projecting outwardly through the flange 1 into 75 openings extending through sockets 5. Jam nuts 22 on the screws 21 may lock the yokes and screws together in any position given them or may be relieved to permit adjustment whereby the chasers may be caused 80 to move inwardly or be permitted to recede any desired amount corresponding to standard or over or undersized threads.

Projecting through the openings 8 in the sockets 5 are cam fingers 30 against which 85 the ends of the screws 21 may abut. These cam fingers are shown as having their inner surfaces tapered outwardly, rearwardly of the die stock as shown at 31, Figs. 2 and 8. These cam fingers are shown as rigidly 90 carried by radial projections on a ring 33 rotatably embracing an annular groove formed at the forward portion of the guiding frame 40, whereby rotation of the ring and cam fingers in relation to the guiding frame is permitted, but the fingers and ring are prevented from longitudinal movement with relation to this frame and are thereby caused to move through the chaser carrying frame. To cause this relative movement of 100 the chaser carrying frame and guiding frame and to insure the accurate progress of the chasers during the thread cutting operation, I have provided master screw threads on a rearwardly extending sleeve 105 42, preferably integral with the chaser carrying frame and engaging internal threads at 43 on the guiding frame. The screw threads have a pitch corresponding to the thread to be cut.

The guiding frame may be of any preferred construction. I have shown a construction which has proven very practical and effective in use; it is preferably in the 5 nature of a sleeve, portions of which are cut away for lightness and which carries radial guides 45 for the clamping jaws 46. Rotatably embracing the frame is a cam plate 47 having a series of cam slots 48 adapted to engage pins 49 rigid with the 10 jaws 46 and adapted to be turned to move the gripping jaws inwardly or outwardly. The periphery of the plate 47 may be knurled if desired or for convenience it 15 may have an outwardly projecting wing 50 for rotating it with relation to the frame to actuate the gripping jaws to move them inwardly or outwardly with relation to the pipe to be threaded. When brought into 20 engagement with the pipe, the clamping may be made more rigid by reason of a screw such as indicated at 52, extending through one of the jaws and provided with a pivoted handle 53 whereby the grip on 25 the pipe may be tightened effectively.

In use the operation of my die stock is as follows:

Assume that the gripping jaws of the 30 guiding frame have been clamped onto a pipe and the set screw 52 tightened, the chasers are now adjusted to cut a thread of the exact diameter desired by relieving the lock nuts 22 and turning the screws 21, which may be accomplished by thrusting 35 a suitable tool through radial openings 23 in the ends of these screws. This moves the yokes 15 inwardly or outwardly as desired. The chasers are then moved to bring the shoulders 13 into engagement with the 40 yokes, the lock nuts 22 again tightened and the threading operation started. The parts at the start of the threading operation are in position shown in Fig. 2 and as the threading progresses the sleeve 42 advances 45 the chaser carrying frame toward the guiding frame and thus along the pipe, being threaded. This moves the pins 21 along the cam surfaces 31 permitting the guiding yokes 15 to move outwardly allowing the 50 proper recedence of the chasers. The chasers are held in position by arcuate plates 60 secured to the frame by screws as at 61 which may be removed whenever desired. As these plates do not entirely cover the 55 face of the frame, ready access is allowed to the screws 21 and lock nuts 22 for all ordinary use of the tool. It will be noted that the yokes 15 have the legs engaging the chasers at right angles thereto and the 60 outward thrust of the chasers is received at three points, namely, the ends of the yokes bearing against the flanges 7 and the screw 21 bearing against the cam fingers 30. It will also be noted that the off-set

surfaces of the chasers are so arranged that 65 the chasers may be removed by withdrawing them inwardly from the chaser carrying frame.

Having thus described my invention what I claim is:

1. In a die stock the combination of a 70 rotary chaser carrying frame, longitudinal cam surfaces, screws abutting said cam surfaces and connected with the chasers and means for moving said screws along said 75 surfaces for adjusting the chasers inwardly or outwardly.

2. In a die stock the combination of a 80 rotary chaser carrying frame, stationary guiding frame, longitudinal cam surfaces, a screw connecting said frames for causing such surfaces to have movement relative to the chasers during the cutting of the thread, screws abutting said cam surfaces and connected with the chasers for adjusting the 85 chasers inwardly or outwardly.

3. In a die stock the combination of a 90 plurality of radially movable chasers, each having a shoulder, bridge members each extending across a plurality of chasers and having shoulders engaging the shoulders on the 95 chasers to resist outward radial movement thereof, means for adjusting bridge members to control the position of the chasers, and guides for the bridge members.

4. In a die stock, the combination of a 100 chaser carrying frame, bridge members each extending across a plurality of chasers and having engagement with said frame at a plurality of points to receive the outward thrust 100 of the chasers and an adjusting element on each bridge member.

5. In a die stock the combination of a 105 plurality of radially moving chasers, each having a shoulder, bridge members each extending across a plurality of chasers and having shoulders engaging the shoulders on the chasers to resist outward radial movement, means for adjusting bridge members to control the position of the chasers, cams for controlling the recession of said adjusting means.

6. In a die stock the combination of a 110 chaser carrying frame, radially positioned chasers therein, bridge members each connected to a plurality of chasers and adapted to receive directly the radial thrust of each chaser engaged thereby, a screw engaging each bridge member, and cams having movement relative to the chaser carrying frame 115 against which said screws may bear to govern recession of the chaser.

7. In a chaser carrying frame the combination of a plurality of radially movable chasers, yokes each extending across two 120 chasers and having shoulders engaging the chasers to prevent outward radial movement, a screw engaging the yokes intermediate of

the chasers, and projecting outwardly with relation to the frame, cam members having sloping surfaces, a guiding frame carrying said cam members permitting rotation but 5 not longitudinal movement thereof and means for causing longitudinal movement of the chaser frame in relation to the guiding frame.

8. In a chaser carrying frame the combination of a plurality of radially movable chasers, yokes each extending across two chasers and having shoulders engaging the chasers to prevent outward radial movement, a screw intermediate of the chasers, and projecting outwardly with relation to the frame, cam members having sloping surfaces to permit recession of the chasers, and guides engaging the ends of the yokes and parallel to the screw.

9. In a die stock the combination of a chaser carrying frame, a plurality of chasers radially movable therein, bridge members each extending across two chasers, coacting shoulders on the bridge members and chasers 25 resisting outward radial movement of the chasers, parallel abutting surfaces engaging and guiding the end of the bridge members, a screw carried by each of the bridge members parallel to said guiding surfaces, cam fingers approximately parallel to the axis 30 of the thread to be cut and governing the recession of the chasers by abutting the ends of said screws, and means for holding the cams against longitudinal movement while

governing the advance of the chasers as they 35 cut.

10. In a die stock the combination of a chaser carrying frame, a plurality of chasers radially movable therein, bridge members each extending across two chasers and resisting 40 outward radial movement of the chasers, surfaces engaging and guiding the end of the bridge members, an adjusting screw carried by each of the bridge members parallel to said guiding surfaces, and removable 45 plates retaining said chasers and leaving an opening for access to said screw.

11. In a die stock, the combination of a chaser carrying frame, two chasers radially movable therein, a bridge member 50 engaging said chasers, means rigid with the frame slidably engaging the bridge member at two points in the vicinity of the chasers respectively, and means for adjusting the position of the bridge member. 55

12. In a die stock, the combination of a chaser carrying frame, two chasers radially movable therein, a bridge member extending across and beyond the chasers, means rigid with the frame slidably engaging the ends 60 of the bridge member on two parallel guiding surfaces, and an adjusting means connected with the bridge member between the chasers.

In testimony whereof, I hereunto affix my signature.

IRA W. NONNEMAN.
